Illino.

UNITED STATES PATENT OFFICE.

JOHN C. HOLLINGS, OF BOSTON, MASSACHUSETTS.

GLOBE OR SHADE HOLDER FOR ELECTRIC LAMPS.

1,346,375.

Specification of Letters Patent. Patented July 13, 1920.

Application filed July 28, 1919. Serial No. 313,915.

To all whom it may concern:

Be it known that I, JOHN C. HOLLINGS, a citizen of the United States, and a resident of Boston, in the county of Suffolk and 5 Commonwealth of Massachusetts, have invented an Improvement in Globe or Shade Holders for Electric Lamps, of which the following description, in connection with the accompanying drawings, is a specification, 10 like characters on the drawings representing like parts.

This invention relates to globe or shade holders for electric lamps and more particularly to such holders for incandescent 15 lamps. The object of the invention is to provide a simple and inexpensive form of holder which will be particularly though not exclusively adapted for high-powered lamps where ventilation is a desirable feature.

20 The invention will be best understood with reference to the following description when taken in connection with the accompanying illustration of one specific embodiment thereof, while its scope will be more 25 particularly pointed out in the appended claims.

In the drawings:—

Figure 1 is a side elevation of a globe 30 holder embodying one form of the invention, there being shown attached thereto a globe partly broken away;

Fig. 2 is a plan view of the globe holder shown in Fig. 1; and

Fig. 3 shows a detail.

35 Referring to the drawings and to the specific embodiment of the invention therein shown, I have provided a foraminous holder 1, preferably formed of wire mesh, which holder acts as the connection between the eye 40 or suspending member 2, by which the holder is attached to any suitable depending support, and the globe-attaching member, herein in the form of a solid rim 3 secured to the peripheral edge of the holder 1 and 45 provided with suitable globe securing screws.

4. Preferably the foraminous holder 1 is given a convex shape which herein approximates a spheroidal shape although that is not essential. The convex shape, however, 50 is not only suitable for the appearance and purpose but increases the supporting strength of the foraminous holder which herein serves as the sole support connecting the globe-attaching rim to the suspension 55 member 2.

While the foraminous holder 1 may be

made of other material, preferably and herein the same is formed of wire mesh constructed out of wire of suitable strength, such, by way of example, as piano wire. For 60 the sake of rigidity such wire may be woven and if desired soldered or otherwise secured at the intersections.

The suspending member 2 may be of any suitable form such as the eye having the 65 central aperture 5 for the reception of the conductors leading to the lamp terminals and may be clamped or otherwise secured to the central portion or apex of the holder 1. The peripheral edges of the wire mesh 70 holder may be secured to the globe-attaching rim 3 in any suitable manner as by soldering or brazing.

The described form of holder provides a maximum amount of ventilation for high-powered incandescent lamps such as nitrogen lamps of which an excessive heating is a characteristic. It throws no substantial shade upon the ceiling and is a strong, durable and simple, cheap construction.

80 While I have herein shown and described for the purpose of illustration one specific embodiment of the invention, it will be understood that the same is not limited to the precise details of construction, shape or form 85 nor to the relative arrangement of parts, but that extensive deviations may be made therefrom without departing from the spirit thereof and that the same is applicable to holders for shades of any type whether 90 globular or otherwise in form.

Claims:

1. A globe or shade holder for electric lamps comprising a wire mesh frame, a shade-attaching rim secured to the edges of 95 said frame and supporting means located at a mid portion of said frame.

2. A globe or shade holder for electric lamps comprising a wire mesh frame having a convex shape, a supporting member at the 100 apex thereof and shade-attaching means at its peripheral edges.

3. A globe or shade holder for electric lamps having shade-attaching means, a suspending member for suspending the same 105 from a depending support and a wire mesh member acting as the sole supporting connection between the suspending member and the rim.

4. A globe or shade holder for incandescent lamps having an open mesh convex foraminous holder provided with a globe-

attaching rim integral with the edges of the open mesh holder and having clamping means engaging directly with the walls of the shade to clamp the latter to the rim.

5 5. A globe or shade holder for incandescent lamps having an open mesh convex foraminous holder, a suspension member arranged at the apex of said holder, a solid

shade-attaching rim at the edges of the open mesh holder and integral therewith and ¹⁰ clamping means engaging directly with the walls of the shade for clamping the latter to the rim.

In testimony whereof I have signed my name to this specification.

JOHN C. HOLLINGS.
